COFFEE MAKER

Walter R. Lorang, 2239 W. Maple Road,
Walled Lake, Mich.

Filed June 13, 1960, Ser. No. 60,924

Term of patent 14 years

(Cl. D2—3)

FIG. 1

Fig. 1 is a front elevational view of the coffee maker embodying my new design.

Fig. 2 is a top plan view thereof; and

Fig. 3 is a side elevational view thereof.

The back of the coffee maker is substantially plain.

I claim:

The ornamental design for a coffee maker, as shown and described.
